UNITED STATES PATENT OFFICE.

FRED J. STEPHENSON, OF HANFORD, CALIFORNIA.

CHECK WRITER AND PROTECTOR.

Application filed July 11, 1925. Serial No. 42,884.

This invention relates to improvements in devices for filling in blank checks, drafts and the like, and especially adapted for use by banks and other business houses in whose course of business a large number of such blanks require filling in.

At present it is customary to fill in the name of the payee and other data on the check or draft by means of an ordinary typewriter, or else by hand, the check being then placed in a separate machine to add the amount to be paid in the well known protective manner, i. e. by means of words or figures which are punched or make a definite impression in the paper rather than merely printing the data on the surface.

These two separate operations require the use of two separate machines and a consequent double handling of the check, consuming considerable time in the aggregate.

The principal object of my invention therefore is to eliminate this double handling of the checks by providing a machine by means of which the necessary typewritten data, as well as the amount of the check in the proper protective words or figures, are all placed on the check without manually handling the check from beginning to end. The operation of filling in the check complete is therefore expedited, and considerable time consequently saved.

The apparatus may be made very compact, so as to occupy relatively little space compared with that necessary for the two individual machines now used, and its cost may also be considerably less than that of said two machines.

These objects I accomplish by means of such structure and relative arrangement of parts as will fully appear by a perusal of the following specification and claims.

In the drawings similar characters of reference indicate corresponding parts in the several views:

Fig. 1 is a front view of the machine.

Fig. 2 is an elevation of the right hand end thereof.

Fig. 3 is a cross section on the line 3—3 of Fig. 1.

Fig. 4 is a longitudinal section taken approximately on the line 4—4 of Fig. 3.

Fig. 5 is a cross section on the line 5—5 of Fig. 4, certain parts being removed to feature the check advancing mechanism as controlled by movement of the type bars.

Fig. 6 is a cross section on the line 6—6 of Fig. 4, with certain parts removed to feature the check advancing mechanism as controlled by movement of the spacer bar.

Fig. 7 is a cross section on the line 7—7 of Fig. 4, with certain parts removed to feature the check advancing mechanism as controlled by movement of the protective impression roller.

Fig. 8 is a fragmentary view showing a sliding bearing mounting for said roller.

Fig. 9 is a fragmentary section enlarged showing a shaft pinion mounting.

Fig. 10 is a similar view showing a shaft ratchet wheel mounting.

Fig. 11 is a similar view showing a hand controlled means for operating the check advancing control shaft.

Referring now more particularly to the characters of reference on the drawings, the numeral 1 denotes a base member of suitable dimensions, with vertical end and back plates 2 and 3 respectively projecting upwardly therefrom. These parts form the main frame of the machine.

Supported by the back member 3 and depending downwardly from the top and a certain distance in front of the same is a plate 4, extending the full length of the machine between the end frames 2. Disposed parallel to and in front of the plate 4 is a similar plate 5, the plates being spaced somewhat from each other to form a check or draft receiving slot, which is open all along the top and at the left hand or discharge end of the machine.

The top of the plate 5 is somewhat lower than that of a plate 4, and flares away from the same, so that it is easy to insert a check into the slot from above.

Intermediate their upper and lower ends the plates 4 and 5 are bent outwardly from each other to form a wider spaced portion 6, in which is vertically slidable a supporting pad 7 which extends the full length of the plates. This pad is mounted on a shaft 8 which has pinions 9 on its ends outside the frames 2. These pinions engage vertical racks 10 mounted on the frames 2, said shaft having a handle 11 on one or both ends to rotate the same and thereby cause the raising or lowering of the pad.

It will therefore be seen that a check inserted between the plates will be supported by the pad 7, and by raising and lowering

the latter, the check may be held at different levels. The portion 6 in which the pad is located is widened over the space between the plates above said pad to prevent the thin check from possibly becoming caught between the pad and the side plates in which it is mounted.

The check is maintained in a predetermined position in the slot and prevented from undesired longitudinal movement by the following means:

Mounted on the back member 3 between the same and the plate 4 are vertical rollers 12, preferably arranged in a number of longitudinally spaced units of two rollers each. These rollers of course project through suitable slots in the plate 4 so as to bear against a check disposed between the plates. The shafts 13 of these rollers are supported from the back plate 3 and extend downwardly below the plates to be rotated in the manner which will be hereinafter set forth.

Arranged to cooperate with the rollers 12 and located outside the plate 5 are idler rollers 14. These rollers are mounted in a swing frame 15 which is pivoted at its lower ends, so that said frame may be drawn outwardly at its upper end, thereby withdrawing the rollers 14 from contact with the rollers 12, and allowing the check to be freely inserted into or removed from the plate slot. The plate 5 is of course also slotted to enable the rollers 14 to project therethrough. A relatively weak spring 16 is applied to the frame 15 to maintain the rollers 12 and 14 in frictional engagement, and handles 17 are mounted at the upper ends of said frame 15 to enable the same to be readily manipulated.

Mounted in front of the plate 5 is a circular type-bar support 18 such as is commonly used in various makes of typewriters.

A plurality of bars 19 carrying type faces on their outer ends are pivoted in the support 18, the support and bars being of course so arranged that when the bars are operated, they all converge to a common point intermediate the top and bottom of the upper portion of the check slot. The plate 5 is cut away as at 21, where such type faces strike when raised, so that the type may engage the check. A vertical platen roller 22 is mounted behind such cut away arrangement and projects through a suitable slot in the plate 4, so that the type will be stopped by the usual hard yet resilient surface behind the check. This roller is rotated in common with the rollers 12, as will be seen later.

The type bars are operated as in common typewriter practice, by key bars 23 turnably mounted on a common supporting shaft 24 and projecting from the front of the machine in a suitable arrangement of two or more horizontal rows. It may here be

noted that the number of type and key bars used may be considerably less than in an ordinary typewriter, since only upper case letters are needed, and various characters necessary on the ordinary typewriter may be omitted.

The key bars are operatively connected to the type bars by suitable linkage 25 arranged so that the type bars will be raised to engage the check when the keys are depressed. The usual form of spacer bar 26 extends the length of the key board in front of the keys, and is attached at its ends to levers 27 preferably fixed on the shaft 24.

The shafts 13 of the rollers 12 and the shaft 28 of the roller 22 are rotated with the depression of any key in a direction to cause a check held between the rollers to be advanced toward the discharge or left hand end of the machine in the following manner:

A horizontal shaft 29 extends longitudinally of the machine under the shafts 13. Bevel gears 30 on the lower ends of the latter mesh with similar gears 31 on the shaft 29. The shaft 28 which is behind the line 90 of shafts 13, is operatively connected to the shaft 29 both by spur gearing 32 and bevel gearing 33. All the bevel gears 31 are slideable on the shaft 29, but are maintained in driving relation therewith at all times by 95 suitable means, such as a transverse pin 34 in the shaft for each gear, projecting into a longitudinal slot 35 in the gear hub (see Fig. 9). The gears are held from longitudinal displacement on the shaft by individual brackets 36 engaging the same and secured to the back frame 3.

Turnably mounted on the shaft 29 adjacent the center of length of the support 18, is a ratchet wheel 37, which is held 105 against longitudinal movement on the shaft by a bracket 38 similar to the brackets 36. This wheel is provided with a clutch face on one end normally engaged by a clutch element 39 fixed on the shaft 29 (see Fig. 110 10). This ratchet wheel is engaged by a pawl 40 mounted on an arm 41 which is turnable on the hub of the ratchet wheel.

Projecting over the top of the bar support 18 for a certain distance and following the curvature thereof is a rigid strip 42 which is supported by horizontal pins 43. These pins project rearwardly from said strip and are slideable in bearing sleeves 44 provided in the back frame 3. A rigid arm 45 depends from said strip behind the support 18 in transverse alignment with the arm 41, and is connected thereto by a link 46. The strip is normally maintained in its forward position by compression springs 47 about the pins 43 (see Fig. 5). The forward edge of the strip 42 is normally so located as to be in the path of movement of all the type bars as the latter are raised, and is engaged thereby and moved rearwardly 120 125 130

when said type bars have been raised to such an extent that any two type faces, if two bars are raised at the same time, will jam together. This prevents the accidental 5 movement of the strip by more than one type bar at a time.

When the strip 42 is thus moved rearwardly, the ratchet wheel 47 is rotated, causing the rotation of the rollers 12 and 22 in 10 a check advancing direction. This mechanism is so proportioned that this advancing movement will cause the type to be impressed on the check in the proper spaced relation. Upon the release of pressure on 15 the strip 42 by the return movement of the type bars, the strip resumes its normal position by reason of the springs 47, and the pawl 40 moves over the ratchet wheel without rotating the same.

20 The depression of the spacer bar 26 effects a similar rotation of said rollers by reason of a ratchet wheel 48 which is mounted on the shaft 29 in the same manner as the wheel 37, and also normally engaged 25 by a clutch element 49 fixed on the shaft 29. This ratchet wheel is engaged by a pawl 50 which is mounted on an arm 51. This arm is moved to rotate the sprocket wheel with the depression of said spacer bar 30 by a suitable linkage 52 between the arm 51 and one of the spacer bar levers 27 (see Fig. 6).

Opposed ribbon spool supports 53 are mounted in front of the plate 5 a certain 35 distance on each side of the opening 21 therein. Said supports are adapted to carry ribbon spools 54 of ordinary character, the ribbon 55 of which extends between the spools across the opening 21 in the plan of 40 striking of the type faces (see Fig. 1). These spools are intermittently and alternately rotated by rotation of the shaft 29, to move the ribbon one way or the other, by means of a suitable shafting arrangement 45 56 for each spool. Such shafting for each spool consists of offset sections, connected by gearing and similar means, as indicated at 56^a to bring the lower end of said shafting in vertical alinement with the shaft 29. On 50 the lower end of each shafting is a bevel pinion 57, the pinions being alternately engaged by bevel gears 58 splined on the shaft 29. The gears 58 are connected together, so that only one at a time can engage the corresponding pinion 55, by rocker arms 59 supported from the base 1. A shift rod 60 connects these two arms, said rod being shifted by means of a hand grip as illustrated at 55 61, or it may be done automatically as is the case with various typewriters.

It will therefore be seen that with the operation of the typewriter features, when filling in the name and other data on the check, said check will be properly advanced from 60 right to left; the platen roller will be rotated

to prevent its becoming pitted in any one place; and the ribbon will be shifted to constantly present a fresh surface to the type.

In order to enable the matter thus typed 70 on the check to be subsequently visible without removing said check from between the plates, the plate 5 is preferably provided with a slot 62 of considerable length and located both to one side of the opening 21 and of course in the vertical plane of the 75 typed matter (see Fig. 4).

After the above data has been filled in the amount to be paid is then added. This could 80 of course be done by the type, by shifting the check upwardly until the type alined with the amount space on the check, but this would not give the protective and non-erasible features now considered necessary.

I therefore provide the following structure:

85 Mounted in longitudinally spaced relation to each other between the left hand end frame 2, and the adjacent end of the support 18 are vertical frame members 63. These members have horizontal slots 64 90 whose axis is on a somewhat lower level than the slot 62. A shaft 65 is journaled in and slidable along said slots, said shaft carrying an impression roller 66. This roller has raised amount-denoting words and other 95 necessary characters as at 67 disposed thereon in suitable transverse and circumferentially spaced relation. (See Fig. 1.)

Links 68 are connected to the shaft 65 and 100 extend to arms 69 depending from a horizontal shaft 70 mounted in the frames 63 parallel to the shaft 65 and in front of the same. A handle bar 71 projects upwardly from the shaft 70, this mechanism being so arranged that when the handle is pulled toward the operator, or away from the plate 5, the roller 66 is advanced toward said plate. A slot 72 is provided in the plate 5 so that the roller may engage the check, and a pitted back plate 73 projects through the 110 plate 4 in alinement with the slot 72, to form a rigid abutment for the movement of the roller. This form of raised word and back plate or stop arrangement is commonly used on check protecting devices, the result being 115 that wording of a semi-perforated form is impressed in the paper. Such wording is of course colored and an ink receptacle 74 having an inking roller 75, is therefore mounted between the frames 63, the roller 120 75 being adapted to engage the roller 66 when the latter is retracted (see Fig. 7).

A turnable knob 76 is mounted on the shaft 65 on one end of the same, so that the roller 66 may be turned to impress any desired wording on the check. This knob is peripherally marked with index numbers, as shown in Fig. 1, arranged in such relation to the wording on the roll 66 that when any index number on the knob faces the opera- 130

tor, the corresponding wording on the roller will face toward the check.

To rotate the shaft 29 so as to advance the check a distance not less than the length 5 of a word on the roller 66 with the return movement of the latter, I provide the following structure:

A vertical lever 77 is pivoted intermediate its ends on one of the frames 63. The upper 10 end of this lever carries a roller 78 which bears against the side of the shaft 65 nearest the plate 5. A spring 79 attached to said lever not only holds the roller 78 in engagement with the shaft, but acts to return 15 said shaft to a normal retracted position after it has been moved by manipulation of the handle 71. From the lower end of the lever a link 80 extends to an arm 81 which is turnably mounted on the hub of a ratchet 20 wheel 82, which in turn is turnably mounted on the shaft 29. A pawl 83 on the arm 81 engages said ratchet wheel said parts being so arranged that the wheel is only rotated with the return of the lever 77 to its 25 normal position. The movement of the lever 77 is such that a rotation of the shaft 29 is had sufficient to effect an advancing of the check a distance at least equal to the length of a word on the roller 66 with each 30 such movement of the lever.

A clutch member 84 is mounted on the shaft 29 and normally engages the ratchet wheel 82 to maintain the same in driving relation with the shaft. The purpose of 35 having the shaft 29 slideable relative to the various bevel gears of the shaft 13, and the clutch elements to engage the various ratchet wheels instead of having the latter fixed on the shaft, is that it is frequently necessary 40 to rotate the shaft one way or the other by hand, which it would otherwise be impossible to do in one direction without disengaging the pawls from their ratchet wheels.

I therefore mount a turning handle 85 on 45 the right hand end of the shaft 29. This handle has a hub 86 provided with longitudinally spaced rows of circumferentially spaced sockets or notches 87 to receive a spring pressed pin or pawl 88 mounted in 50 the adjacent end frame 3 (see Fig. 11). A spring 89 acts on the shaft 29 to normally hold the various clutch elements engaged with their respective ratchet wheels.

When it is desired to rotate the shaft by 55 hand in a check advancing direction, this may of course be done without pulling the shaft out, since the various ratchet wheels then rotate freely under their pawls. To reverse the direction of said shaft it must 60 be pulled out until the member 88 engages the inner row of sockets. This will disengage the clutch elements from the ratchet wheels and the latter will not be moved permitting the shaft to freely turn. The different bevel gears however still remain in 65

mesh and in driving relation with the shaft owing to the brackets 36 etc. which prevent displacement of the gears 31 from their meshing positions. In either case the ribbon spool drive gears 58 are not disturbed, 70 since the shaft 29 is freely slideable in said gears, and the positions of the latter are independently controlled. The circumferential spacing of the sockets 87, such that with the seating of the pawl in adjacent sockets, 75 the shaft is rotated a distance sufficient to advance the check the length of one type space.

In operation the check to be filled in is 80 placed in the right hand end of the slot between the plates from the top thereof, the frame 15 being pulled out so as to separate the rollers 14 from the rollers 12. The check then rests on the supporting pad 7, and the latter if necessary is moved up or down by 85 turning the handle 11, still holding the frame 15 out, until the space on the check in which the name of the payee etc. is to be filled in will be at the proper level relative to the type. The frame 15 is then released 90 so that the rollers engage the check, and the latter is then advanced by the hand rotation of the shaft 29 if necessary until said space to be filled in occupies the proper position lengthwise relative to the opening 95 21.

The data is then filled in by manipulation of the type in the usual manner.

This done, the check is again shifted if necessary as before, to properly align the space in which the amount is to be filled in 100 with the impression roller 66. The handle 71 is then manipulated the necessary number of times to impress the necessary data on the check. The latter may then be removed, either from above or from the left 105 hand end of the check slot, upon pulling out the frame 15 as before to separate the rollers.

It is to be understood that while I have 110 here shown and described a certain arrangement of the different features and a certain form of operating and connecting mechanism between the different parts, such arrangement and mechanisms are capable to a great extent of being altered without in the 115 least affecting my invention.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A machine for filling in checks and the 130

like comprising supporting means for the check, manually operable bars having type faces for enabling data to be typed on the check while thus supported, an impression roller whose surface is provided with data in the form of words to be impressed on the check, mounted in connection with the supporting means to one side of the type-bars, means for enabling said roller to be moved into engagement with the check at will, a mechanism for advancing the check longitudinally in the supporting means, means for actuating said mechanism to advance the check a distance not less than the width of a type-face when the type-bars are actuated, and means for actuating said mechanism to advance the check a distance not less than the length of a word on the roller when the latter is actuated.

2. A machine for filling in checks and the like comprising supporting means for the check, manually operable bars having type faces for enabling data to be typed on the check while thus supported, an impression roller whose surface is provided with other data to be impressed on the check, mounted in connection with the supporting means to one side of the type-bars, means for enabling said roller to be moved into engagement with the check at will, a mechanism for advancing the check longitudinally in the supporting means, such mechanism including transverse pairs of vertical rollers between which the check is held, shafts extending from one row of such rollers, a horizontal shaft operatively connected to all said first named shafts, means for turning said horizontal shaft a certain amount when any type bar is moved to engage the check, and means for turning said horizontal shaft a greater amount when the impression roller is actuated.

3. A machine for filling in checks and the like comprising supporting means for the check, manually operable bars having type faces for enabling data to be typed on the check while thus supported, an impression roller whose surface is provided with data in the form of words to be impressed on the check, mounted in connection with the supporting means to one side of the type-bars, means for enabling said roller to be moved into engagement with the check at will, a mechanism for advancing the check longitudinally in the supporting means, independently operating means for actuating said mechanism to advance the check when any type bar and the impression roller are actuated, and hand operated means for enabling said mechanism to be actuated to move the check in either direction without

disturbing said type bar and roller operating means.

4. A machine for filling in checks and the like comprising vertical and transversely spaced plates forming a slot for the reception of a check, transversely spaced and vertically disposed rollers projecting through the plates to frictionally engage the check, certain ones of said rollers being rotatable for moving the check longitudinally, a vertically movable pad disposed between the plates for supporting the bottom of the check, means mounted in fixed relation to the plates for imprinting data on the check, means operable at will for raising and lowering the pad to enable the check to be aligned vertically with respect to the imprinting means, and means for enabling the frictional engagement of the rollers with the check to be released at will to permit the check to follow the movement of the pad.

5. A structure as in claim 4, in which said last named means comprises a frame independent of the plates pivoted longitudinally thereof and in which one of the sets of rollers is mounted, handle means for moving said frame to draw the rollers thereon away from the other rollers, and spring means tending to move the frame in the opposite direction.

6. A machine for filling in checks and the like including vertical and transversely spaced plates to receive a check in an upstanding position, means arranged in connection with the plates for imprinting data on a check located therebetween, and a vertically movable pad between the plates for supporting the check; the space between the plates for the extent of movement of the pad being increased but substantially centralized relative to the spacing above and the pad fitting snugly between the plates in such increased space, whereby to prevent the bottom of the check catching between the pad and plates.

7. A structure as in claim 2, in which said first named horizontal shaft turning means comprises a ratchet wheel on the shaft, a pawl engaging the ratchet and a lever mechanism between said pawl and the type-bar structure; and said last named horizontal shaft turning means comprises an independent ratchet wheel on said shaft, a pawl engaging said ratchet wheel, and a lever mechanism between said pawl and the impression-roll operating means.

In testimony whereof I affix my signature.

FRED J. STEPHENSON.
